UNITED STATES PATENT OFFICE.

ANTHONY SEUFERT, OF ALBUQUERQUE, NEW MEXICO.

SOUND AMPLIFIER.

Application filed March 29, 1926. Serial No. 98,203.

It is a purpose of the present invention to provide an improved sound amplifier especially including a tone arm, wherein the construction and arrangement of the parts thereof are such as will permit the stylus of the sound box to cooperate with all makes of disc records.

As is well known, the sound groove of one make of disc record has its bottom surface undulated, so as to cause vibrations to the diaphragm of the sound box through the medium of the stylus, while the side walls of the sound groove of another make of record have the undulations, causing lateral movements to the stylus and thus creating lateral vibrations to the diaphragm of the sound box.

With these facts in view, another purpose of the present invention is to provide, in a sound amplifier, what is known as a tone arm portion which will permit the stylus of the sound box to cooperate with these two constructions of records by simply twisting certain portions of the tone arm, so as to allow the stylus to play in the sound groove.

Still another purpose is to provide, in a sound amplifier, a pliable cap or sound deflector to be fastened on the face of the sound box in order to deflect all the sound back through the tone arm, which is continuous from the sound box to the outlet terminus of the amplifier, hence reproducing the human voice in a loud, clear, broad effect with volume and sonority unequaled by other constructions.

The invention comprises further features and combinations of parts to be hereinafter set forth, shown in the drawings and claimed.

40 In the drawings:

Figure 1 is a view in section of a talking machine cabinet, showing the improved amplifier and its tone arm section as applied, the stylus of the tone arm section operating upon a record which causes lateral vibrations of the stylus.

Figure 2 is a plan view of the cabinet showing a record on the turn-table, illustrating the amplifier applied with its tone arm section in elevation and its outlet terminus portion in dotted lines.

Figure 3 is a sectional view of a talking machine cabinet with the amplifier applied, the tone arm cooperating with a record

which imparts vertical vibrations to the diaphragm of the sound box.

Figure 4 is a horizontal sectional view of Figure 1, taken just below the plane of the sound board.

Figure 5 is a sectional view on the plane indicated by the line 5—5 of Figure 1.

Figure 6 is a detail sectional view through the sound box, showing the rubber sound deflector.

While, in the illustrated embodiment of the invention, its application is shown in connection with a talking machine, it is obviously applicable to radio in connection with loud speakers or wherever megaphonic sounds are desired. A portion of the talking machine cabinet 1 is illustrated, being provided with what is commonly called a top-plate 2, this latter supporting the amplifier 3 and particularly the tone arm section 4 thereof. The amplifier comprises an amplifying section 75 proper 5 which is housed in the cabinet, including an elbow 6 which telescopes an extension 7 of a sleeve 8.

The sleeve 8 is carried by the top-plate 2 and the extension 7 passes through the board, 80 there being an annular flange 9 on the sleeve which receives fastening means 10 to secure the sleeve to the top-plate. The elbow 6, as previously stated, telescopes the extension 7, there being a rubber gasket 11 to insure a 85 close fit and prevent the escape of sound and to insure full vibrations of the cabinet as well as the sound-board.

The amplifying section proper comprises the parallel parts 12 and 13 which are connected by the bend 14, there being a bend 15 at one end of the portion 13 which in turn connects to an elbow 16, as at 17. The elbow 16 in turn connects at 18 to an outlet terminus 19 which has conical or diverging walls 95 to permit of the expansion of sound as it leaves the amplifier.

The tone arm section comprises an elbow 20 which is swivelly connected at 21 to the sleeve 8, there being a semicircular bend 100 22 connected at 23 to the elbow 20. This bend lies in a plane laterally to the elbow 20 and is in turn connected at 24 to a straight section of tubing 25. An elbow 26 is swivelly mounted at 27 in one end of the straight section 25, so as to permit of vertical movements of the elbow which is in turn connected at 28 to a straight section 29 of the tone arm.

This section 29 comprises two parts 30 and 31 which have adjacent flanged ends 32 clamped together by set-screws or the like 33. The section 31 is capable of axial movement relative to the section 30 and after the section 31 has been adjusted, the set-screws or the like may be tightened to hold the section 31 in position. In other words, the section 31 may be positioned so as to hold the sound box 34 whereby its stylus 35 may operate in the sound groove of the record, which groove causes vertical vibrations of the stylus. It is possible to adjust the part 31 so as to arrange the stylus to engage with the sound groove of a record which causes lateral vibrations of the stylus. In either case, the sound box is capable of accommodating itself to the irregularities of the record through the medium of the swivel joint 27 and the swivel joint 23.

The part 31 of the straight section 29 is connected to an elbow 36 which receives the sleeve 37 of the sound box 34. The sound box includes a rubber cap or sound deflector 38 which is fitted over the face of the sound box, covering the diaphragm, which deflects

all the sound back through the tone arm which is continuous from the sound box to the outlet terminus of the amplifier.

While the amplifier herein described is shown as comprising a specified number of sections, it is obvious that this number may be increased any reasonable amount with corresponding increased beneficial effects.

The invention having been set forth, what is claimed is:

In a talking machine amplifier, a tone arm, a sound box, a pair of elbows connecting the sound box with the tone arm, one of said elbows having a swivel connection with the tone arm and the other a swivel connection with the sound box; the adjacent ends of said elbows being provided with flanges of which one is provided with diametrically disposed arcuate slots of approximately ninety degrees in length, and set screws mounted in the flange of the other elbow and traversing the slots in relative angular or turning movement of the two elbows.

In testimony whereof he affixes his signature.

ANTHONY SEUFERT.
